UNITED STATES PATENT OFFICE

HANS HART, OF MUNICH, GERMANY

FOLDING BOAT

Application filed May 11, 1929, Serial No. 362,230, and in Germany September 19, 1928.

I have filed applications for this patent in Germany on Sept. 19, 1928; on February 13, 1929; in Austria on March 22, 1929; in Switzerland on March 25, 1929.

5 The trueness of the keel line of folding boats frequently becomes impaired after a short period of use or after long storage, in consequence of the unavoidable inequality of tension in the wooden frame and in the 10 covering material or in consequence of warping or of other changes of form due to the inherent elasticity of the materials used in the construction of the boat. This loss of 15 trueness or warping of the keel impedes the straight motion of the boat and also makes turning more difficult, thus entailing greater effort and dexterity in handling the boat.

The present invention relates to a folding boat, in which this unavoidable loss of trueness of the keel line may be permanently compensated for by simple and reliable means.

According to the present invention the keel line can be adjusted by means of movable 25 keel elements without in any way prejudicing or impairing the other constructive elements of the boat.

The accompanying drawings show a form of the folding boat according to the present 30 invention, Fig. 1 being a plan view, Fig. 2 a view in perspective of a constructional detail, Figs. 3 and 5 views of two forms of construction of the boat stem, and Fig. 4 a section of a constructional detail of Fig. 3.

35 In the form of the invention here shown a keel piece or element (a) is provided for each half length of the boat, said keel piece being firmly connected at its outer extremity to the stem (b) of the boat, the term stem 40 here applying to both ends of the boat; the inner end of the keel piece (a) is free to swing about, with the stem as centre, and can be fixed in the desired position by suitable means; in the present case these means 45 consist of a set screw (d) arranged on the keel end and sliding in a slit (c¹) of the rib (c) of the boat; by means of the screw (d) the inner end of the keel piece (a) can be fastened in position after adjustment; the 50 means of adjustment are similar for both

halves of the boat. It will be obvious that the connection of the keel piece (a) to the stem (b) and to the rib (c) or other suitable part of the boat body can be attained in various ways; the adjustable connection of 55 the inner end of the piece (a) may, for instance, consist of a screw spindle and nut, which is self locking and permits of adjustment of the keel line under way.

The application of the above-described 60 contrivance in practice is as follows:

If the keel line of the boat has lost its trueness, as shown by the dotted line in Fig. 1, so that the keel pieces (a) form an obtuse angle, it is only necessary to swing the inner ends 65 of the keel pieces (a) until they are in alignment, as shown by the full line in Fig. 1, and then to fix said ends in this position by means of the set screws (d). The boat is thus again given a straight keel and the normal 70 easy motion and capacity of maneuvering of the boat again restored. In the accompanying drawings the adjustment angle of the keel pieces has been greatly exaggerated, it being 75 in practice only necessary to move the inner ends of the pieces (a) an inch or two, which adjustment is without influence on the other parts of the boat body. On the other hand, if desired, this adjustability of the keel line 80 may be utilized to purposely deflect the keel from the straight line, the keel then acting as a rudder, in order to counteract the effect of a side wind or to facilitate motion in a continued curved line.

85 Suitable fittings are provided at each end of the boat for the watertight connection of the canvas deck and sides, said fittings making the attachment of the canvas covering to the body of the boat unnecessary and thus preventing any injurious distortion of the 90 canvas when adjusting the keel pieces (a).

95 Figs. 3 and 4 show one form of construction of these fittings, which consist of two form plates (e, f), between which the end of the deck canvas (g) and the two edges of the side pieces (h) are firmly clamped with the help of screws or other suitable means; in this way a firm and at the same time watertight connection is attained and the canvas covering 100 of the boat is perfectly independent of

the adjusting movement of the keel pieces (a). The form plates (e, f) may advantageously be made of metal, vulcanite or other suitable material and may be further provided with suitable elastic packing pieces to increase the watertightness. The upper plate may also serve as a base for fastening a boat ring or for a socket for fixing a flagstaff.

Fig. 5 shows another form of the fitting, according to which the latter consists of a single plate (e) which is thick enough to allow of the attachment of the side canvasses (h), either direct or with the help of a suitably formed outer bridle (b).

Having now described my invention in detail, I declare that what I claim as new is:

1. In a folding boat, a laterally adjustable keel member.

2. In a folding boat, a body element, a stem, a keel member connected to the stem for lateral swinging movement, and means adjustably engaging the keel member to said body element whereby to hold the keel member in laterally adjusted positions.

3. In a folding boat having a body element and stems at the bow and stern, keel sections each connected to a corresponding stem and adapted for lateral swinging movement, and means for adjustably engaging each keel section to a body element to hold the keel section in its adjusted position.

4. In a folding boat, a plurality of transversely extending ribs, stems at the bow and stern of the boat, keel sections each connected to a corresponding stem and adapted for lateral swinging movement, each keel section at its inner end being adjustably engaged with one of the ribs whereby to hold the keel section in laterally adjusted positions.

5. In a folding boat, a stem at the forward and rear ends of the boat, intermediate ribs, deck and side canvasses, a keel section connected to each stem and operative to move the stem, and means associated with the intermediate ribs for holding the keel sections in adjusted positions.

In testimony whereof I affix my signature.
HANS HART.
